ONE REVOLUTION TRIP MEANS

Berthold Knauer, East Norwalk, Conn., assignor
to Pitney-Bowes, Inc., a corporation of Delaware

Application April 21, 1945, Serial No. 589,556

6 Claims. (Cl. 188—81)

1

This invention relates to a one revolution control mechanism and is particularly arranged for use in a crank operated postage printing machine, wherein a postage impression is printed on mail matter during each machine cycle of operation.

As provided by the present invention, a trip or stop release is adapted to be effected by a slight reverse motion of the crank handle. This produces an improved operation of the machine in that it prevents the operator from accelerating the crank unduly, when printing several successive impressions, a situation which frequently occurs in machines where tripping is adapted to be effected on the forward stroke of the crank.

It is the object of this invention therefore to provide, in a crank controlled postage printing machine, means whereby the tripping operation for each succeeding operation is effected by a slight reverse movement of the crank.

With the above and other objects in view, which will appear as the description proceeds, the invention resides in the combination and arrangement of parts and in the details of construction hereinafter described and claimed, it being understood that various changes in the precise embodiment of the invention herein disclosed may be made within the scope of what is claimed without departing from the spirit of the invention.

A preferred embodiment of the invention is illustrated in the accompanying drawings, wherein:

Fig. 1 is a side elevational view of a one revolution crank operated machine, including a trip and one revolution control mechanism;

Fig. 2 is a plan view of a portion of Fig. 1, showing the one revolution control mechanism on an enlarged scale, and is taken in the direction of the arrow 2 of Fig. 1;

Fig. 3 is an end view of the one revolution control mechanism with part in section, and is taken along the lines 3—3 of Fig. 1;

Fig. 4 is a view similar to Fig. 3, with the control mechanism shown in the initial reverse crank movement position;

Fig. 5 is also a view similar to Fig. 3, with the control mechanism shown in stop release position as effected by the initial forward crank motion; and

Fig. 6 is another view similar to Fig. 3, with the control mechanism shown during a cycle of revolution.

Referring to the drawings in detail, the device comprises a support 10 having bearings

2

11—11, within which a crank shaft 12 is adapted to rotate. A crank handle 13 is fixed to one end of the crank shaft 12 to provide a means for rotating said shaft. A spiral gear 14, freely mounted on said crank shaft, is adapted to mesh with another spiral gear 16 to provide a drive for a main drive shaft 15. The drive between the crank shaft 12 and the gear 14 is effected by means of a coupling collar 17, which collar is fixed to the crank shaft 12 by means of a pin 18, and is coupled with the worm gear 14, as at 19. The coupling connection comprises a tongue projection 21 on the collar 17, and groove 22 in a projecting hub 23 of the worm gear 14. Clearance is provided, as indicated at 24, to effect lost motion, for a purpose to be later described.

The one revolution control for limiting the rotation of the crank shaft, comprises a projection 25 on a hub 26, which hub projects from the worm gear 14 in a direction opposite to the hub 23. A stop arm 27a, on a rocker member 27, normally extends into the path of the projection 25 to thus obstruct movement of the crank shaft 12 after each revolution thereof. The rocker member 27 is fixed to a shaft 28, which shaft is rotatively supported in a bearing 30 provided in the support member 10. The rocker member 27 further includes a second arm 29 extending sidewaysly, which arm is adapted to cooperate with a cam portion 31 on the hub 26.

A rocker lever 32 is freely mounted on the shaft 28 and has an upwardly extended arm 33 and a downwardly extended arm 34. A roller 35 is mounted on the upwardly extended arm 33. To the rear of the rocker lever 32 is another arm 36, which arm is pinned to the shaft 28 at 36a and has a pin 37 extending from the lower end thereof. A spring 38 has its coils surrounding hub portions 39 and 41 extending from the rocker lever 32 and arm 36 respectively, and has its ends extending downwardly, with one end 42 engaging a lip 43 projecting from the arm 34, and another downwardly projecting end 44 engaging a lip 45 projecting from the arm 36. By means of said spring, the arm 34 is urged against the lip 45 and both the lever 32 and arm 36 normally move as an integral unit but have sufficient flexibility to allow independent movement of the rocker lever 32 when the crank moves to its home position, as in Fig. 3.

The stop member 27 is normally locked in its stop position through the engagement of a stop shoulder portion 40 on a stop plate 46 with the pin 37 projecting from arm 36. The stop plate 46 is pivotally mounted upon a stud 47 and has

a downwardly projecting detent portion 48, which is normally engaged by a detent spring 49 to normally maintain the stop plate in a blocking position relative to the pin 37 projecting from the arm 36.

A trigger member 51 is pivotally mounted upon a pin 52, projecting from the face of the stop plate 46, and has a trigger finger portion 53 normally projecting into the path of a lug 54 extending from a hub 50 pinned to the crank shaft. Said hub 50 forms a part of stop release cam 61, to be later described. A spring 55, coiled around the pin 52, has one end looped over the trigger finger 53, and the opposite end bearing against a boss 56, extending from the stop plate 46. Another finger 57, projecting from the trigger member 51, normally bears against the boss 56 due to the pressure exerted by the spring 55, as indicated in Figs. 2, 3, 4, 5 and 6. An upwardly extended portion 58, of the stop plate 46, normally lies in the path of a lug 59, also projecting from the boss 26.

A stop release cam 61, fixed to the end of the crank shaft 12, has its cam surface bearing against the roller 35, on the rocker lever 32, and is adapted to effect rocking of the stop arm 27a from its stop position, after the crank has received a slight reverse motion from its normal home position.

In operation, the above-named mechanism functions in the following manner:

With the parts in their home position, as shown in Fig. 3, the cycle of operation is started by rotating the crank shaft in a clockwise or reverse direction, as viewed from Fig. 3. This will cause the lug 54 to engage the trigger finger 53 and effect rocking of the stop plate 46 about its pivot stud 47, as indicated in Fig. 4. The stop shoulder 40 on said stop plate 46 is thus removed from the path of the pin 37, and the detent 48 is removed from its detent position relative to the spring 49. Movement of the stop plate 46 is limited by the engagement of a projection 62 with an abutment 63, forming a part of a support 10. The restricted movement of said stop plate 46 also limits the reverse motion of the crank shaft 12.

Reverse motion of the crank shaft 12 is permitted without causing rotation of the main drive shaft 15, due to the lost motion connection provided by the tongue and groove 21 and 22, previously described.

The forward or operating motion of the crank shaft can now be effected in that the stop arm 27a is free to be rocked, as indicated in Fig. 5, when the cam 61 is rocked in a counter-clockwise direction, and the high point 64 of said cam engages the roller 35. Referring to Fig. 5, it will be seen that the stop has been removed from the path of the projection 25, which movement occurs during the take-up of the lost motion provided by the tongue and grooved portions 21 and 22. With the stop removed, the rotation of the crank shaft can now be made without interruption for one complete revolution.

Resetting operations are effected during the rotation of the shaft 12 as follows: The trigger portion is reset through the engagement of the lug 59 with the portion 58, projecting from the stop plate 46, and the stop arm 27a is positively returned to its home position by the engagement of cam 31 with the arm 29 of the rocker member 27. Therefore, after the crank shaft has moved through the complete revolution the projection 25 will again engage the stop arm 27a and all other portions of the device will have been

reset to their normal positions, as shown in Fig. 3. Having described the invention what is claimed is:

1. A one revolution control device, comprising, 5 a hand crank shaft including a stop engaging member movable therewith, a shiftable stop element normally positioned in the path of the stop engaging member to obstruct movement when the crank shaft reaches its home position, blocking means obstructing movement of the stop element when the crank shaft is in its home position, means to permit limited reverse rotation of the crank shaft after the said crank shaft reaches said home position, and means operable 10 during the reverse rotation of the crank shaft to remove the blocking means from a blocking position and thereby free the stop element.

2. A one revolution control device, comprising, 20 a hand crank shaft including a stop engaging member movable therewith, a shiftable stop element normally positioned in the path of the stop engaging member to obstruct movement when the crank shaft reaches its home position, blocking means obstructing movement of the stop element when the crank shaft is in its home position, 25 a lost motion connection operable by the crank shaft drive to permit limited reverse rotation of the crank shaft after the said crank shaft reaches said home position, means operable during the reverse rotation of the crank shaft to remove the blocking means from a blocking position relative to the shiftable stop, and means operable on the forward movement of the crank shaft to effect movement of the stop element 30 out of the path of the projecting element.

3. A one revolution control device, comprising, 35 a hand crank shaft including a stop engaging member movable therewith, a shiftable stop element normally positioned in the path of the stop engaging member to obstruct further movement when the crank shaft reaches its home position, blocking means obstructing movement of the stop element when the crank shaft is in its home position, means to permit limited reverse 40 rotation of the crank shaft after the said crank shaft reaches said home position, means operable during the reverse rotation of the crank shaft to remove the blocking means from a blocking position relative to the shiftable stop, and a cam 45 provided by the crank shaft on its forward motion and engageable with the shiftable stop element to move said stop element out of the path of the projecting element.

4. A one revolution control device, comprising, 50 a rotative element, a hand crank drive for said rotative element, a movable stop normally urged into an obstructing position relative to said rotative element, a second stop normally set in a blocking position relative to the movable stop, means to permit slight reverse rotation of the hand crank drive when in a home position, and means connected with said drive and operable 55 during reverse rotation to effect movement of the second named stop to a non-blocking position relative to the movable stop.

5. A one revolution control device, comprising, 60 a rotative element, a hand crank drive for said rotative element, a movable stop normally urged into an obstructing position relative to said rotative element, a second stop normally set in a blocking position relative to the movable stop, means to permit slight reverse rotation of the hand crank drive when in a home position, means connected with said drive and operable during 65 reverse rotation to effect movement of the second

named stop to a non-blocking position relative to the movable stop, and means driven by the crank drive and operably associated with the movable stop to move said stop out of an obstructing position on the following movement of the crank in a forwardly direction.

6. A one revolution control device, comprising, a rotative element, a hand crank drive for said rotative element, a movable stop normally urged into an obstructing position relative to said rotative element, a second stop normally set in a blocking position relative to the movable stop, a second rotative element connected with said drive, a lost motion connection between the drive and first named rotative element to permit reverse movement of the drive without effecting movement of the first named rotative element, said second rotative element being adapted to effect movement of the second named stop to a non-

blocking position relative to the movable stop, and means driven by the crank drive and operably associated with the movable stop to move said stop out of an obstructing position on the following movement of the crank in a forwardly direction.
